TOOL SHARPENING APPARATUS

William H. McGill, Winchester, Mass.

Application January 3, 1936, Serial No. 57,375.

5 Claims. (Cl. 51—158)

This invention relates to apparatus for facilitating the hand sharpening of edged tools, such as chisels, gouges, blades, and others of the type in which it is important to have the edge ground or sharpened to a uniform or other predetermined bevel.

Various devices designed to accomplish this object have been proposed heretofore but those of which I have been able to learn have been of such a nature as to restrict or hamper the movements required in performing certain of these hand sharpening operations. Such movements include not only free movements of the tool over the stone while its edge is held in contact with the grinding surface, but also freedom to pick up the tool at any instant to examine its edge.

To devise an apparatus of the general character above designated which will avoid the objections just described, constitutes the chief object of the present invention.

The nature of the invention will be readily understood from the following description when read in connection with the accompanying drawing, and the novel features will be particularly pointed out in the appended claims.

In the drawing,

Figure 1 is a perspective view, with some parts broken away, of an apparatus constructed in accordance with this invention;

Fig. 2 is a plan view of the apparatus illustrated in Fig. 1;

Fig. 3 is a vertical, sectional view through a portion of the base and the guide plate mounted thereon, showing the provision for adjustment of the latter relatively to the base;

Fig. 4 is a sectional view through the tool holder; and

Fig. 5 is a front elevation of a different form of holder designed for use in sharpening gouges.

Referring first to Figs. 1 and 2, the apparatus there shown comprises a base 2 which may conveniently be made of cast iron or any other suitable material. In the upper side of this base a socket 3 is provided to receive a grindstone or equivalent sharpening device 4. For many purposes it is desirable to use a circular stone, as shown, and to have one side of the stone of a coarse, fast-cutting material, while the opposite side is of a much finer grained and slower cutting composition. For this purpose the socket 3 preferably is made somewhat larger in diameter than the stone so that the latter can conveniently be lifted out of it, reversed and replaced.

At one side of the stone 4 the base 2 supports

a guiding plate 5. Preferably this plate is made of hardened steel, although this is not always necessary. When the apparatus is in use the plate 5 is stationary, but it is mounted for vertical adjustment relatively to the stone, this 5 mounting comprising a cup-shaped member 6, of relatively short vertical dimensions, but provided with a screw threaded shank 7 supported in an internally threaded bushing 8 with which the base 2 is equipped. By fitting the threads 10 tightly sufficient friction is provided between these parts to hold the plate against accidental change of adjustment, while still permitting the part 6 to be revolved to raise or lower it.

Assuming that the tool to be sharpened is a 15 hand plane blade 10, such a blade is mounted in a holder 12 comprising a yoke-shaped body member provided with a slot through which the blade may be slipped freely, and a clamping screw 13 threaded through the upper arm of the 20 yoke and provided above said arm with a thumb piece 14 and below it with a foot 15 adapted to bear on the shank portion of the blade or other tool 10. By tipping the tool and the yoke, one 25 relatively to the other, until the two edges of the blade 10 are in contact with the opposite vertical arms of the yoke, the blade will be centered in the holder. Then by turning down the screw 14 the blade can be securely clamped against the 30 base piece of the holder.

Projecting from the lower side of the yoke 12 is an arm 16, rigid with the part 12, and having a ball 17 mounted in its lower extremity. The walls of the socket in which the ball is supported are so crimped over that they retain the ball effectively, while at the same time permitting the ball to revolve freely around its own center.

When the blade has been secured in the holder, as above described, the assembly is positioned as illustrated in Figs. 1 and 2 with the beveled 40 edge of the blade resting on the upper surface of the stone 4 and the ball 17 riding on the horizontal surface of the plate 5. The workman then moves the blade over the surface of the stone, exactly as he would in hand sharpening without 45 the aid of any guiding device. Such movements usually include a somewhat circular motion of the blade on the stone, the edge of the tool being moved over practically the entire face of the stone as the sharpening operation progresses so 50 that the stone will be kept level and localized wear will be substantially avoided. During all of these movements the angle of the blade due to the fact that this angle is determined by the 55

distance between the blade and the surface of the ball **17** at its point of contact with the plate **5**. This distance remains constant notwithstanding the movement of the blade over the stone. Thus the workman is relieved of the difficult operation of maintaining the blade continuously at the same angle, which is absolutely essential in order to grind the edge to a uniform bevel.

10 Adjustment of the angle of the tool on the face of the stone **4** can be made by changing the relative elevation of the stone and the guiding plate **5**, or the length of the arm **16**. Preferably, however, this is accomplished by the screw mounting of the plate, as above described, and as shown in Fig. 3. It will readily be observed that if the plate is revolved toward the right, Fig. 1, it will be lowered, thus tending to grind the heel of the bevel more rapidly, whereas if the plate is 15 revolved in the opposite direction the blade will be tipped up so that more of the grinding operation will be confined to the extreme edge of the blade.

Attention is directed to the fact that the only 20 contact between the holder and the guide plate **5** is one of surface engagement, the ball moving freely over the upper surface of the plate in any direction as the sharpening operation progresses. This is important for the reason that as said 25 operation proceeds, the workman lifts the blade **10** from time to time and examines its edge to see whether or not the bevel is correct, and whether the edge is sharp enough. Toward the completion of this operation he will test the edge 30 on his thumb, or in any other way to which he is accustomed. If he finds that the bevel is not right, he will make suitable adjustment to correct the difficulty. If the edge is still dull he will 35 continue with the sharpening operation until finally he has produced the condition which he desires. However, the fact that he can lift the 40 blade off the stone at any time and handle it exactly as he would if the holder were not on it, and replace it again instantly without disturbing 45 any adjustment, is an important practical advantage. In other words, this apparatus requires no change in the hand sharpening practice or 50 method but it gives the workman the advantage of maintaining the correct bevel constantly without effort on his part. At the same time the workman can perform the sharpening operation 55 more rapidly, both because of maintaining the exact bevel continuously and also for the reason that greater power and pressure can be applied, especially in the roughing operation.

In order to prevent the lower ball end of the 60 guide member **16** from running off the edge of the guide plate **5**, the holder in which this plate is mounted preferably is provided with an upright arm or margin **18**, closely surrounding the plate and projecting above it. The outer cylindrical surface of this member may be knurled, as shown 65 in Fig. 1, in order to facilitate the rotation of this holder in making the adjustment above described.

When the sharpening operation has been completed the screw **13** is backed up, thus releasing the blade **10** and permitting the workman to withdraw it from the holder. Whenever a blade is inserted and centered in the manner above described, the greater part, if not all, of this centering operation will be performed automatically by the twisting of the blade in the holder as the clamping screw **13** is tightened up. This same operation centers the blade with reference to the 70 guiding arm **16**.

Such a holder as that illustrated in Figs. 1, 2 and 4 can be used with a great variety of edged tools. Some tools, however, and some blades will require a special form of holder. One such form is illustrated at **20** in Fig. 5, this holder being 5 designed for use in sharpening gouges. The shank of the gouge **21** is supported on the tapered walls of the body portion of the holder, and it is clamped against them by a screw **22**. In sharpening a gouge, however, a transverse rocking 10 movement of the tool on the stone is necessary in order to present different portions of the curved edge of the tool to the stone. At the same time the angular relationship of the tool to the stone should be maintained in order to produce a uniform bevel. This result may be conveniently accomplished by equipping the holder with a templet **23**, the lower edge of which has the same transverse curvature as the gouge. The edge of this member can be both moved over the plate **5** 15 in any direction and also rocked on this plate as the sharpening operation progresses, thus enabling the workman to grind the entire edge to the correct bevel but relieving him of the effort and skill required to hold the tool continuously in the 20 correct angular relationship to the stone. The templet **23** may consist of a thin plate inserted in a saw cut or slot in the holder **20** and clamped securely, but removably, by a screw **24**.

While I have herein shown and described a 30 typical embodiment of my invention, it will be evident that the invention may be embodied in other forms without departing from the spirit or scope thereof.

Having thus described my invention, what I de- 35 sire to claim as new is:

1. In a tool sharpening apparatus, the combination of a flat, relatively stationary grindstone, a tool holder comprising a yoke-shaped body member, a base piece connecting the arms of 40 said member, a screw carried by said yoke for engagement with the base piece to clamp the tool securely but releasably in the holder for the sharpening operation, a guide plate, a support for holding said stone and said plate positioned horizontally and closely adjacent to each other, said tool holder including an arm rigid therewith and in axial alignment with said screw and having a round ended guiding member at its lower end arranged to bear on the upper face of said plate 45 and freely movable in any direction on said face, said member cooperating with said plate and said holder to determine the angle at which said tool will be held on the surface of said stone while the tool is moved over the stone, and means 50 for preventing the movement of said guiding member off the edge of the plate.

2. In a tool sharpening apparatus, the combination of a flat, relatively stationary grindstone, a base having a socket therein to receive 60 said stone and to support the same in a horizontal position, said socket and stone being constructed to permit the angular adjustment of the stone into a series of different positions therein whereby the wear on the stone may be distributed more uniformly, a horizontal guide plate mounted on said base closely adjacent to said stone, a tool holder constructed to clamp the tool to be sharpened securely but releasably therein for the sharpening operation, said tool holder including a guiding member arranged to bear on the upper face of said plate and freely movable in any direction on said face, said member co- 65 operating with said plate and said holder to determine the angle at which said tool will be held 70 75

on the surface of said stone while the tool is moved over the stone, and means adjustable to change the angular relationship of said tool to the grinding face of said stone.

5. 3. In a tool sharpening apparatus, the combination of a flat, relatively stationary grindstone of circular outline, a base having a circular socket therein to receive said stone and to support the same horizontally for rotative adjustment in said socket, a tool holder constructed to clamp the tool to be sharpened securely but releasably therein for the sharpening operation, a horizontal guide plate mounted on said base adjacent to said socket, said tool holder including 10 a guiding member arranged to bear on the upper face of said plate and freely movable in any direction on said face, said member cooperating with said plate and said holder to determine the angle at which said tool will be held on the surface of said stone while the tool is moved over the stone, and means adjustable to change the angular relationship of said tool to the grinding face of said stone.
20. 4. In a tool sharpening apparatus of the character described, a grindstone, a guide plate, a support for the stone and plate, a yoke-shaped tool holder having a slot therethrough for the reception of the shank of the tool, said slot having end and bottom walls and being wider than said shank and permitting lateral movement of the

shank in the holder, said movement being limited by the end walls of said slot, a clamping screw threaded through the upper wall of the yoke-shaped portion of the holder for exerting pressure on said tool perpendicular to said plane of lateral movement to clamp said tool in said slot against said lower wall, an arm rigid with said yoke-shaped portion and extending therefrom in axial alignment with said screw, and said arm having an end face curved about a center lying in said axis and adapted to bear on said guide plate.

5. 5. In a tool sharpening apparatus, the combination of a flat, relatively stationary grindstone, a base having a socket therein to receive said stone and to support the same in a horizontal plane, said socket and stone being constructed to permit the angular adjustment of the stone in said horizontal plane into a series of different positions therein whereby the wear on the stone may be distributed more uniformly, a horizontal guide plate over which the tool is guided during the sharpening thereof mounted on said base closely adjacent to said stone, screw threaded means supporting said plate for adjustment vertically relatively to said stone, and a tool holder provided with a guide arm adapted to rest upon and move freely over the surface of the guide plate.
